UNITED STATES PATENT OFFICE.

GUSTAVUS A. CRAMER, OF PITTSBURG, PENNSYLVANIA.

DESIGN FOR A STICK-PIN OR SIMILAR ARTICLE.

SPECIFICATION forming part of Design No. 30,358, dated March 21, 1899.

Application filed February 17, 1899. Serial No. 705,899. Term of patent 34 years.

To all whom it may concern:

Be it known that I, GUSTAVUS A. CRAMER, a citizen of the United States, residing at Pittsburgh, in the county of Allegheny and State of Pennsylvania, have invented and produced a new and original Design for a Stick-Pin or Similar Article, of which the following is a specification.

This invention relates to a new and original design for a stick-pin or similar article; and it has for its object to provide a design of this character that shall be both useful and ornamental.

The leading feature of the design resides in a body having the configuration of a horseshoe and the figure of a heart arranged inside and within the plane of said horseshoe body.

While the essential or characteristic feature of the design resides in the representation of a miniature horseshoe and the figure of a heart arranged therein, the invention involves several minor features, which may be enumerated as follows: The horseshoe-body having its toe and heel calks of a triangular shape, and said toe-calk being provided on the inclined face thereof with the picture or representation of an open book, the representation of a book-mark ribbon arranged between the open pages of the book and connecting the picture of the latter with the upperend of the figure of the heart, and the representation of separate right arms extended inwardly from the heel ends of the shoe-body with the two hands clasped immediately beneath the point of the figure of the heart.

An additional minor feature of the design is the curved side portions of the shoe-body, having a series of jeweled settings representing the nail-holes and similar settings arranged within the figure of the heart.

In the drawings, Figure 1 is a plan view of a stick-pin or similar article embodying the design contemplated by the present invention. Fig. 2 is an edge view thereof.

Referring to the accompanying drawings, the numeral 1 designates an ordinary stick-pin carrying the ornament or design forming the subject-matter of the present application, and the frame or body of said ornament or design is designated in the drawings by the numeral 2. The body 2 is in the form of an ordinary horseshoe and is provided with a single triangular toe-calk 3, projected from one side thereof, and at its heel extremities with the triangular heel-calks 4. In the present invention the inclined face of the triangular toe-calk 3 is provided thereon with the picture of an open book 4^a, having arranged between the open pages thereof a book-mark ribbon 5, which is represented as hanging below the toe-calk 3 and connecting with the open wide end of the figure of a heart 6, which is arranged inside and within the plane of the horseshoe-body 2. The said horseshoe-body 2 is further provided, in the opposite curved side portions thereof, with a series of jeweled settings 7, which represent the nail-holes of the shoe, and similar jeweled settings 8 are located within the figure of the heart 6. 70

The design also includes the representation of separate right arms 9, extended inwardly from the heel ends of the shoe-body and shown with the hands 10 thereof clasped immediately below the point of the figure of the heart 6, the arrangement of the clasped right hands 10 being such as to give the appearance of the heart being supported thereby.

What is claimed is—

The design for a stick-pin or similar article, herein shown and described.

In testimony that I claim the foregoing as my own I have hereto affixed my signature in the presence of two witnesses.

GUSTAVUS A. CRAMER.
